UNITED STATES PATENT OFFICE.

CHARLES H. CLARK, OF SPRINGFIELD, OHIO.

SCRUBBING DEVICE.

1,146,308.

Specification of Letters Patent. Patented July 13, 1915.

Application filed April 10, 1914. Serial No. 830,953.

To all whom it may concern:

Be it known that I, CHARLES HARNER CLARK, a citizen of the United States, residing at Springfield, in the county of Clark and State of Ohio, have invented certain new and useful Improvements in Scrubbing Devices, of which the following is a specification.

This invention comprehends certain new and useful improvements in scrubbing devices and has for its primary object to provide a scrubbing device of the fountain type wherein a stream of water may be forced through a soap containing head and into a cleaning cloth secured around said head.

Another object is to provide a device of this character in which the parts will be of extremely simple construction and the head will be formed in two sections, one of which is perforated and adapted to have the cleaning cloth secured around its end.

A further object is to provide a device of this character which may be readily connected with a spigot or the like and which may, if desired, include an auxiliary sectional soap container adjacent the spigot or other water supply to which the device is connected.

A still further object is to generally improve and simplify the construction and operation of devices of this character and increase the efficiency thereof without increasing the cost of the same.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which,

Figure 1 is an elevational view of my improved device, Fig. 2 is an enlarged longitudinal section thereof, the handle being shown in elevation with the free-end thereof broken away, Fig. 3 is a detail cross sectional view taken on the plane of line 3-3 of Fig. 2, Fig. 4 is an elevational view, partly in section showing a modified form of my device connected with a spigot, and, Fig. 5 is an enlarged detail longitudinal section through the head and parts carried thereby.

Referring in detail to the drawings by numerals, 1 designates the handle, upon the reduced forward end 2 of which is secured the tubular portion 3 of the device, by which the inner section 4 of the head is carried and from which projects the sleeve 5 to which the flexible hose 6 is secured, said sleeve 5 projecting at an angle from said tubular portion 3 of the device.

The outer end of the inner head section 4 is threaded, as shown at 7, whereby the outer substantially semi-spherical head section 8 may be threaded upon the same, the complete head formed by the head sections 4 and 8 being of substantially egg shape and being adapted to contain soap, (not shown), the outer head section 8 being perforated, as shown at 9, whereby water may be forced by way of the flexible hose 6, sleeve 5, and tubular section 3 of the device, through the head sections 4 and 8 and out of the head by way of the perforations 9, said water being compelled to pass the soap within the head.

The outer head section 8 is provided with an annular groove 10 adjacent the threaded edge of said head section, by pressing the material of the head section 8 inwardly, as will be readily understood. A cleaning cloth or mop 11 has one end secured around the outer head section 8 and held in position by means of a transversely split ring 12 engaged around the same and pressing the cloth in the annular groove 10, it being understood that the ring 12 is formed of suitable resilient material.

In Figs. 4 and 5 I have shown a modified form of the device, in which the head 13 is formed in one piece with the tubular portion 14 of the device and is of substantially spherical form. In this form, instead of forming the head in the two sections, as in the preferred form, the outer portion or end of the head is formed integral with the inner or main portion thereof and is perforated, as shown at 15, the cloth 16 being secured around the outer portion of the head by means of the transversely split ring 17 serving to press the cloth or mop in the annular groove 18 formed in the head, at a suitable distance inwardly of the perforations 15. In this modified form, the tubular portion 14 is secured to the reduced portion 19 of the handle 20, the same as in the preferred form, and the sleeve 21 projects at an angle from the tubular portion 14 and has the flexible hose 22 secured thereto. The

hose 22, however, is connected with the lower semi-spherical section 23 of an auxiliary soap container 24, said lower semi-spherical section 23 being connected with a similar upper semi-spherical section 25, as shown at 26, whereby the sections may be readily separated for the purpose of placing soap therein or removing the same. Projecting from the upper semi-spherical section 25 of the auxiliary soap container 24, is the short connection 27 which connects with the small portion of the funnel-shaped member 28 adapted for removable engagement with a spigot or the like 29.

From the foregoing, it will be clearly apparent that I have provided a scrubbing device which will be of extremely simple construction and operation and which will be highly efficient and effective in use. It will also be apparent that if desired, the auxiliary soap container 24 may be dispensed with and the flexible hose 22 connected with the short connection 27 or secured directly to a spigot or other water supply. It will further be apparent that many other minor changes in the details of construction and arrangement of parts may be made within the scope of the appended claims without departing from the spirit of my invention or sacrificing any of the advantages thereof. It will be understood that the auxiliary soap container shown in the modified form, may be of any shape desired.

What is claimed is:—

1. A device of the class described comprising a tubular member having a head formed on one end, a handle connected with the opposite end of said tubular member,

said head having a perforated portion, a cloth engaged around said head and inclosing the perforated portion thereof, means for securing the cloth in position, a sleeve projecting from said tubular member, a flexible fluid supply member secured to said sleeve, and a soap container positioned in the path of said flexible member.

2. A device of the class described comprising a tubular member, a handle engaged with one end of said tubular member, a fluid discharge head upon the opposite end of said tubular member, an arm projecting from said tubular member, a hollow flexible member secured to said arm and adapted to be connected with a source of water supply, and a sectional spherical soap containing member carried by said flexible member.

3. A device of the class described comprising a flexible fluid conducting member, a semi-spherical soap container section carried by said flexible fluid conductor, a second semi-spherical soap container section connected with the first mentioned section, means carried by the last mentioned section for connecting the same with a source of fluid supply, a tubular member, a discharge head carried by said tubular member, a handle secured to said tubular member, and means for connecting the flexible fluid conducting member to the tubular member.

In testimony whereof I affix my signature in presence of two witnesses.

CHAS. H. CLARK.
